UNITED STATES PATENT OFFICE.

CARL LENGYEL, OF CANTON, OHIO.

STAND FOR SHINING SHOES.

Application filed May 1, 1924. Serial No. 710,368.

My invention relates to movable foot supports on the stand so as to facilitate the engagement of the seat by a person whose shoes are shined, to eliminate the danger of soiling the clothing of a person while getting on or off the stand, and also to provide a step which automatically collapses when the foot rest is in the vertical position, thus making room for the free movements of the workman.

An object of the invention is to provide a simple, efficient and inexpensive device which, in addition to serving as a foot rest will also serve as a step for facilitating the walking of a person on to or from the stand.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Fig. 1 is a side elevational view of the stand.

Fig. 2 is a front elevational view of the stand showing the left foot rest.

Fig. 3 is a front elevational view showing the cooperation between the right and left hand foot rests respectively in the lowered position.

Referring to the drawings:

Fig. 1 shows the foot rest in a normally upright working position. 10 shows the foot rest post. 11 shows a supporting socket. 12 is a bolt which pivots the foot rest in the socket. 13 represents an automatic lock of the usual type which engages a recess or notch in the object to be held, with spring 14 to maintain it closed when the foot rest is swung in place. 15 is a step plate notched at its lower end which is supported dependently by pivot means 16. 17 is a lug on post 10 which initially prevents plate 15 revolving in wrong direction on 16 as an axis when in lowered position of the foot rest. When the foot rest is raised from the lowered position to the upright position shown, 17 also assists in guiding the lower edge of 15 into its socket 11. 18 is a stop which helps support the plate in a horizontal position after the same has revolved downward through an angle of

90° on pivot 16 when the foot rest is in the 55 position shown by dotted lines.

In operation, it is seen that when the foot rest is in a normal upright position the plate lies in the same plane with the foot rest, and the lower end of 15 fits in the socket 11 and is maintained there by lock 13, thus comprising a supporting base for the foot rest. The lug and the stop thus limit the angular rotation of 15 to an angle of 90°.

When in the lower position as shown by 65 Figure 4, the plates, being free from the socket, fall inwardly and together form a complete step being held in position by stops 18.

An important feature of the invention is 70 that the step of the lowered position is transformed into a supporting brace when in the upright position and hence interferes in no way with the operations of shining shoes.

Another important feature is that this device may be attached to the conventional type of elevated stand without any alterations of the same, except the removal of one or both of each pair of the old fixed type of foot rests. It is only necessary, however, to 80 replace but one of each pair of the old rests, since it merely requires one of the movable type to create a step for the platform, although of course two make a wider step.

I claim:

1. A stand for shining shoes comprising a seat, a foot rest post associated therewith, and mounted to swing to and from the seat to an elevated and a lowered position, a folding step pivotally depending from the post, 90 a stop on said post, whereby the step is maintained horizontally when the said post is in the lowered position.

2. A stand for shining shoes comprising a seat, a foot rest post adapted to be moved 95 to and from the seat to an elevated and a lowered position, means for pivotally supporting said post, a plate, pivotal means on said post supporting said plate in a vertical position, integral means on said post, forming a stop for said plate, whereby a step is 100 formed when the post is in the lowered position.

3. In combination a stand, a right and a left foot rest post adapted to be raised or 105 lowered, a plate pivotally supported by each post, a stop on the left and the right side of each post respectively, sockets supported by

said stand, pivoting means in said sockets for said posts, whereby when said posts are lowered, the plates swing toward each other and form a step.

5 4. A shoe shining stand comprising a support, a socket mounted on said support, a pivot means associated with said socket, a foot rest post on said pivot means, a plate hingedly supported from said foot rest post 10 and having a notch formed near one end, stopping means on said foot rest post to guide said plate into said socket, and locking means on said support adapted to engage in said notch whereby said post is 15 maintained in operative position.

5. A stand for shining shoes comprising a foot platform, a foot rest post associated therewith and mounted to swing above and below the level of the platform, means comprising a swinging plate hinged to said post 20 for forming a step in said lowered position and means cooperating with said plate for transforming said step into a support for

the post when above the platform level to fixedly support the post in an upright 25 position.

6. A combined foot rest and step for the purposes described, comprising, a socket, a foot rest, means for pivotally securing it in said socket, a plate, means for hingedly securing said plate to said rest, means cooperating with said rest to limit the movement of the plate to a perpendicular position relative to the plane of said rest.

7. A combined foot rest and step for the 35 purposes described, comprising, a socket, a foot rest, means for pivotally securing said rest in said socket, a plate cooperating with said socket, means for hingedly securing said plate to said rest, means cooperating 40 with said rest to limit the movement of the plate to a position determined by the plane formed by the rest and the socket, means for locking said plate in said socket.

CARL LENGYEL.
